Application May 2, 1944, Serial No. 533,685

6 Claims. (CL 309—2)

1

This invention relates to tubular articles and has particular reference to one-piece domed engine cylinders, but the invention is not limited to that use. Engine cylinders, particularly cylinders of air-cooled aeronautical engines, are usually composed of two separate parts, viz., the barrel and the head, which are screwed and shrunk or otherwise permanently secured together, both barrel and head being provided with either integral or attached heat-radiating fins. By reason of this construction, the size of the cylinder head is disproportionately great, so that the air-cooling space between adjacent cylinder heads on inline air-cooled engines is small, requiring complicated and extensive finning to obtain adequate heat dissipation. If the barrel and the head could be made in one piece with a steel liner taking all the stresses, the cylinder head wall thickness would be materially reduced. However, the nature of the material commonly used for the wearing surfaces of the cylinder, particularly the barrel, precludes formation of the cylinder head as a part of the barrel because then the material which is satisfactory for the barrel must be made substantially heavier in the head portion in order to have adequate strength to sustain the combustion pressure. If, however, the head portion of a one-piece cylinder could be made to have different physical characteristics so as to be stronger than the cylinder barrel wall for the intended purpose, the desirable aforementioned advantages would be realized.

In accordance with the present invention, a one-piece cylinder is provided which consists of cast material for the wearing surfaces of the barrel portion and material with different physical characteristics in the head or dome portion, so as to enable it to safely withstand the stresses to which it is subjected in use.

The preferred cylinder of this invention is formed by casting, preferably centrifugally, a substantially uniform-diameter tube of the material which is satisfactory for the barrel portion of the engine cylinder, such as, for example, chromemolybdenum steel of the order of S. A. E. specification No. 4140. The tube so formed is then deformed at its upper end under such conditions that its physical characteristics are changed from a casting to the equivalent of that of wrought metal, with concomitant increase in its physical strength without requiring material increase in its wall thickness, except where that may be desirable for providing additional strength or material for making valve seats, and the like, or both.

These desirable attributes for the cylinder head portion are obtained by working one end of the cast tube into a closed dome by means of suitable shaping devices, such as rollers or dies,

2

preferably while the material is in the cold state, although heat may be externally applied if desired. In so shaping the free end of the tube, the material achieves a temperature suitable for working, owing to the friction of relative movement between the tube and the shaping die or tool, as the die or tool and the tube are rotated at high speed relatively to each other around an axis coincident with that of the tube. 5 By properly shaping the die or tool and the co-operating mandrel positioned within the tube, the material may be formed into virtually any desired shape and thickness, including thickened portions for greater strength, valve seats, and the like, as described. The finished one-piece cylinder formed in the manner described is then preferably heat-treated in the usual way accorded to the barrel portion of the cylinder, and the one-piece cylinder has adequate strength 10 for use in a high speed aeronautical engine, while retaining the desirable properties of a casting in the barrel or wearing portion.

It will be seen that this invention provides a one-piece cylinder which, after being fitted with the usual cooling fins formed, cast, shrunk, or otherwise applied thereto, has all of the desirable characteristics of the usual two-piece cylinder, but with reduced dimensions in the head area permitting improved heat flow and desirable increased heat radiating finning with consequent enhanced cooling efficiency at the head portion, while providing desired physical properties in the direction of piston travel.

For a more complete understanding of the invention, reference may be had to the accompanying drawings, in which:

Figure 1 illustrates one form of apparatus for making the one-piece cylinder of this invention;

Figs. 2 and 3 illustrate elevation and plan views, respectively, of an alternative apparatus for making the one-piece cylinder of this invention; and

Fig. 4 illustrates an enlarged axial section of a finished cylinder of this invention, with the usual cooling fins and with the Rockwell hardness index of various sections thereof indicated thereon.

Referring to Fig. 1 of the drawings, a straight thin-walled tube 10 provided with the mounting flange 11 is cast of steel, preferably chromemolybdenum steel of S. A. E. specification No. 4140 (.8-1.1 Cr, .15-.25 Mo), or similar metal, which has good strength and wearing characteristics for use as thin-walled cylinder barrel stock, but which may be materially thickened when used as cylinder head stock, to increase its strength to withstand cylinder head combustion pressures. The tube 10 is preferably cast centrifugally, with the integral mounting flange 11, 55 so as to obtain a dense casting and to isolate

the dross on the inner surface, where it may be readily machined off in accordance with known practice.

The tube 10, being a casting, may not readily be hammered or swaged to close the upper end thereof to provide the cylinder head by the usual methods. Accordingly, the physical characteristics of the material should be altered to enable the shaping desired and also to provide material having the necessary strength required for the cylinder head, without materially increasing its thickness.

The combined forming of the cylinder and conversion of the metal at the free end of the tube 10, shown by the dotted lines in Fig. 1, is effected by a spinning operation, preferably by means of a concave non-rotatable die 12 having an inwardly tapering inner face 13 merging into the contour desired for the cylinder head. The curvature of the recess 14 in the die 12 is such as to obtain the desired shape and thickness of the head portions and may be adequate to provide material for machining the valve seats, if desired.

The cast tube 10 is mounted in a chuck 15 by means of suitable clamps 16 engaging the mounting flange 11 so as to rotate at high speed about an axis coincident with the axis of the tube 10. The die 12 is advanced slowly toward the tube 10 by suitable power means such as by hydraulic pressure, and to that end an axial extension 17 on the die 12 is fitted with a piston 18 moving in a cylinder 19 mounted rigidly on the bed 20 of the forming machine. The end of the cylinder 19 is closed by the plug 21 through which the fluid under pressure is supplied by tube 22 for advancing the die 12 toward and into engagement with the tube 10, the rate of advance of the die 12 being controlled by a suitable valve in pipe 22, not shown.

In making the cylinder of this invention with the apparatus shown in Fig. 1, the tube 10 is rotated at high speed and simultaneously the die 12 is advanced to engage its free end. Owing to the taper 13 of the concavity in the die 12, a reducing pressure is exerted on the tube end so as to develop substantial heat in the cast metal by friction, and to simultaneously gradually compress the free end of the hot tube so as to reduce its diameter. As the die 12 slowly advances, the metal which surface 13 progressively engages is likewise heated by the friction and the metal is worked and substantially flows to conform to the contour of the die 12, until the free end shown in dotted lines in Fig. 1, is reduced to the dome shape 23, which is preferably thicker at the center 26 and thins progressively as it merges into the wall portion 24.

During this hot working, the cast metal is, in effect, altered into a wrought metal, the change including a transition zone T being indicated by the shading in Fig. 4. The continuation of the frictional heat as the end of the tube is compressed into the tip of the head 26 is sufficient to effect a sort of welding action, so that the tip edges are closed to form continuous metal across the dome 23 at all points.

Preferably, the interior of the tube 10 adjacent its free end is supported by a mandrel 25 having its tip or head shaped to the contour desired for the interior surface of the finished cylinder head. As shown in Fig. 1, the contour of the head of the mandrel 25 is such as to provide greater thickness of material at the center or tip 28 of the cylinder head, that is to say, the radius of curvature of the mandrel 25 at its tip or head

is greater than the radius of curvature of recess 14 of the die 12 at the center of its recess, although it may have the same curvature as the die recess 14, and the die 12 will not be advanced as far toward the mandrel head, whereby increased thickness of dome 23 is obtained. By variously shaping the mandrel 25 and the recess 14 in die 12, virtually any desired thickness or configuration for the head 23 may be obtained, as will be readily understood.

Instead of employing the preformed die 12 for working the cast steel into the desired head shape, as described in connection with Fig. 1, a roller 27, shown in Figs. 2 and 3, rotating in a suitable yoke 15 pivoted on the bed 20 of the forming machine about a vertical axis 28 substantially coincident with the center of curvature of the dome, may be employed. In this case the end of the cylinder tube is preferably preheated and the roller 27 gradually swung from the dotted line position shown in Fig. 2 about its pivot 29 to the full line position shown as the material is worked and shaped in the manner described, friction contributing the major part of the heat required for the shaping operation. An interior mandrel similar to mandrel 25 in Fig. 1 may be used, depending upon requirements.

The finished cylinder retains the physical characteristics of the cast steel, such as S. A. E. No. 4140 mentioned, along the barrel portion B, where it is required for the piston engaging surface. However, the head portion H has altered physical characteristics, owing to the working produced by the forming operation of this invention, and those physical characteristics are similar to those obtained in wrought metal in the sense that the material has greater physical strength than the original cast metal, so as to withstand the pressures to which it is subjected in use on an engine.

The transition zone T between the barrel portion B and the head portion H shows a gradual change from crystalline structure of the cast portion B to the crystalline structure of the wrought portion H, the zone T, having a relatively coarse crystalline structure which is augmented when overheating results during working at that point. Consequently, close control of temperature is required in zone T to prevent overheating or burning and to maintain a relatively fine crystalline structure at that point comparable with that in zones B and H.

Heat treatment of the entire finished cylinder according to the heat treatment usually accorded the barrel portion B for S. A. E. 4140 steel, viz., heating to and holding at about 1650° F. for about one-half hour, cooling in air, heating and holding at about 1550° F. for about twenty-five minutes, quenching in oil, and finally tempering by heating to and holding at about 1100° F. for about two hours, results in a substantially uniform grain structure in areas B, T and H; in the nature of a refined sorbitic structure.

Before heat treatment, in an experimental operation, the hardness of the finished one-piece cylinder ranged from 24 to 25 Rockwell "C" hardness for the straight or barrel portion B of the cylinder, approximately 34 Rockwell "C" hardness in the zone T, and 30 to 32 Rockwell "C" hardness in the dome H, as indicated by the indices shown on the axial section of Fig. 4.

The cylinder thus formed may be completed for mounting on the engine crankcase at flange 11 by providing it with cooling fins in the usual way, as indicated by way of illustration by the dotted

lines in Fig. 4. This finning may be applied by casting cooling fin and valve port material on the entire cylinder and milling fins and ports therein, by casting a muff with suitable fins, or by shrinking a jacket of heat transfer material thereon, with or without completed fins previously formed, or the like, such completing operations accordingly forming no part of the present invention. Suffice it to say that the one-piece cylinder of this invention is susceptible to the usual machining and other finished operations accorded cylinder barrels and heads.

The entire cylinder wall may be made as thin as is desirable, and hence serve as a strength liner for an enveloping structure, which may include the air cooling fins, cooling liquid jacket and the like, or it may be made as thick as required throughout, or various portions thereof may be thickened in the manner described so as to serve as the sole strength member for the cylinder, to which may be applied cooling fins or cooling liquid jackets imparting little or no strength to the cylinder as a whole, or the tube may be so formed as to provide part of the strength needed in use with the enveloping structure completing the strength requirements, and the like. Various methods may be employed for adapting the one-piece cylinder of this invention to the requirements of the engine to which it is to be applied, this invention not being limited to the particular use to which the cylinder is to be put, or limited to the particular methods of forming it, which are described herein. Thus, as indicated, friction need not be solely relied on to furnish the heat required to raise the temperature of the metal to the semi-plastic working point, but heat may be added, either by directly heating the end of the tube at least partially to the working temperature with friction completing the heating, or the die in Fig. 1 may be heated to supply all or part of the heat or portions of the die recess may be heated to various degrees to supply additional heat as at the center of the die recess to aid in closing the center or tip of the cylinder dome, and the like. Various other changes in the invention may be made within the scope of the appended claims.

I claim:

1. As an article of manufacture, a one-piece internal combustion engine cylinder part formed of metal, having a substantially uniform chemical composition throughout and comprising a straight-sided tubular barrel portion having substantially the physical characteristics of cast steel, and a dome-shaped head portion having substantially the physical characteristics of wrought steel.

2. As an article of manufacture, a one-piece internal combustion engine cylinder part formed of metal, having a substantially uniform chemical composition throughout and comprising a straight-sided tubular barrel portion having substantially the physical characteristics of cast steel, a dome-shaped head portion having substantially the physical characteristics of wrought steel, and an intermediate portion between said barrel and head portions having physical char-

acteristics changing progressively from substantially cast steel adjacent said barrel portion to substantially wrought steel adjacent to said head portion.

3. As an article of manufacture, a one-piece internal combustion engine cylinder part, comprising integral barrel and head portions, both composed of metal of substantially uniform initial chemical composition and physical characteristics throughout, the physical characteristics of the metal constituting the head portion having been altered as compared to the physical characteristics of the metal constituting the barrel portion, and the chemical composition of said entire part remaining unaltered.

4. As an article of manufacture, a one-piece internal combustion engine cylinder part, comprising a substantially straight-sided tubular barrel portion formed of metal having physical characteristics suiting it for cylinder barrel service, and a dome-shaped cylinder head portion merging into said barrel portion and formed of metal having different physical characteristics than said barrel portion metal and suiting it for cylinder head service.

5. As an article of manufacture, a one-piece internal combustion engine cylinder part, comprising a substantially straight-sided tubular barrel portion having physical characteristics suiting it for cylinder barrel service, and a dome-shaped cylinder head portion merging into said barrel portion and having different physical characteristics than said barrel portion and suiting it for cylinder head service, said cylinder head portion having greater wall thickness than said barrel portion.

6. As an article of manufacture, a one-piece internal combustion engine cylinder part, comprising a substantially straight-sided tubular barrel portion formed of metal having physical characteristics suiting it for cylinder barrel service, a dome-shaped cylinder head portion formed of metal having different physical characteristics than said barrel portion and suiting it for cylinder head service, and an intermediate metal portion merging into said barrel and head portions and including metal having different physical characteristics than the metal of said barrel and head portions.

HALEX JOHNSON.
